CLAIM

The ornamental design for a ladies' platform shoe sole, as shown and described.

DESCRIPTION

FIG. 1 is a right side elevational view of a ladies' platform shoe sole showing my new design; the broken line disclosure being for illustrative environmental purposes only and forming no part of the design;

FIG. 2 is a rear elevational view thereof;

FIG. 3 is a bottom plan view thereof;

FIG. 4 is a left side elevational view thereof;

FIG. 5 is a front elevational view thereof; and

FIG. 6 is a top plan view thereof.
